UNITED STATES PATENT OFFICE.

FRANZ S. THOMAS, OF SALEM, INDIANA.

SAWMILL ATTACHMENT.

SPECIFICATION forming part of Letters Patent No. 591,305, dated October 5, 1897.

Application filed June 19, 1897. Serial No. 641,502. (No model.)

To all whom it may concern:

Be it known that I, FRANZ S. THOMAS, of Salem, in the county of Washington and State of Indiana, have invented certain new and useful Improvements in Sawmill Attachments; and I do hereby declare the following to be a full, clear, and exact description of the invention, such as will enable others skilled in the art to which it pertains to make and use it, reference being had to the accompanying drawings, which form part of this specification.

This invention relates to sawmill attachments, and the object is to provide a turn-block of simple and improved form for assisting in turning the log upon the carriage to proper position for sawing.

The invention consists in the novel features of construction, and in the combination and arrangement of parts hereinafter fully described and claimed, and illustrated by the accompanying drawings, in which—

Figure 1 is an elevation, partly in section, of my improvement, the same being in inoperative position. Fig. 2 is a similar view of the same in operative position. Fig. 3 is a plan view.

Skid A, over which logs are rolled to carriage B, is formed with longitudinal depression C, open a portion of its length at D and at the rear end of opening C' forming abutment E. Inclined track F is arranged in the forward portion of opening C with its upper end extending to the top surface of the skid, and adapted to slide on the track is the metallic-bound block G, having its top and front edge curved, as shown at G'. Link H is arranged to move freely in opening C and is hinged at its forward end to block G, while at its rear end it is secured to rock-arm I by top hinge J; said rock-arm being secured to shaft K, journaled transversely in the skid.

When not in use, the block is in lowered position on the track, as seen in Fig. 1; with its top surface flush with the top plane of the skid and its rear edge engaging abutment E. When link H and arm I are straightened out with their adjacent ends squarely engaging, (see Fig. 2,) the turn-block is projected and rigidly held. The top edge of arm H is reduced backward to form shoulder L, and when the arms are alined, as just described, this

shoulder is raised to engagement with abutment E, so that a doubly-secure holding means for the block is provided.

For operating shaft K the same is provided with cogged segment M, which meshes with a similar segment on shaft N, and on this last-mentioned shaft is an arm O, connected by link P with operating-lever Q. In mills where the sawyer stands on the carriage side of the saw the arm O, link P, and lever Q are preferably arranged in lowered position beneath the floor, as shown in dotted lines.

The operation of the device will be readily understood by those skilled in the art. The block when not in use is in lowered position and entirely out of the way of the logs in being moved to the carriage. After sawing one side of the log and it is desired to turn same to saw another side the block is raised and rigidly held, as described, and the log being turned thereagainst, as shown in Fig. 2, is turned automatically to proper position, the curved inclination of the head causing the log to move back on the carriage in proper position for sawing.

While the description of my invention is in the singular as regards the turn-block, it is my intention to arrange one at each end skid of the log-support, so that the log is turned uniformly its entire length, or, if desired, more than two blocks may be provided, and, in fact, such will be the case in mills of unusual length, shaft K being, of course, of sufficient length to operate the arms for all the blocks. Coiled spring R, arranged, as shown, on shaft K, counteracts the weight of the arms when turned down and renders the adjusting operation more easy.

Having thus fully described my invention, what I claim, and desire to secure by Letters Patent, is—

1. The combination of a skid formed with a transverse abutment, a log-turning block movable vertically therein, an actuating mechanism, and a shouldered link connecting the block and actuating mechanism, the shoulder of the link engaging the skid-abutment when the block is raised, thus locking the latter in elevated position, substantially as shown and described.

2. The combination of a skid formed with an abutment, an inclined track therein, a turn-

block slideable on the track, an actuating mechanism, a link connecting the block and actuating mechanism and at its top formed with a shoulder, the link extending longitudinally of the skid and adapted to engage its shoulder with the skid-abutment after moving the block forward and upward on the track, substantially as shown and described.

3. The combination of the longitudinally-recessed skid formed at its top with a transverse abutment, the inclined track in the forward end of the recess, the block slideable on

the track, a link hinged at its forward end to the block and on its top formed with a shoulder adapted to engage the abutment as described, an actuating-shaft, and a rock-arm on the shaft hinged to the rear end of the said link, substantially as shown.

In testimony whereof I affix my signature in presence of two witnesses.

FRANZ S. THOMAS.
